(74) *Attorney, Agent, or Firm* — Quarles & Brady, LLP

(57) **CLAIM**

The ornamental design for a motor mount and bulkhead, as shown and described.

DESCRIPTION

FIG. 1 is a perspective view of a motor mount and bulkhead showing my design.

FIG. 2 is a front elevational view of the design shown in FIG. 1.

FIG. 3 is a back elevational view of the design shown in FIG. 1.

FIG. 4 is a left elevational view of the design shown in FIG. 1.

FIG. 5 is a right elevational view of the design shown in FIG. 1.

FIG. 6 is a top view of the design shown in FIG. 1; and, FIG. 7 is a bottom view of the design shown in FIG. 1.

In the drawings, the broken lines depict environmental subject matter only and form no part of the claimed design.

1 Claim, 7 Drawing Sheets
